(57) **CLAIM**

The ornamental design for a grip for a wire handle, as shown and described.

DESCRIPTION

FIG. 1 is a bottom side perspective view for a grip for a wire handle showing my new design;

FIG. 2 is a bottom plan view thereof;

FIG. 3 is a top plan view thereof;

FIG. 4 is a front elevation view, the rear elevation view being a mirror image thereof;

FIG. 5 is a front sectional view taken along lines 5-5 from FIG. 3 thereof;

FIG. 6 is a left plan view, the right plan view being a mirror image thereof;

FIG. 7 is a left sectional view taken along lines 7-7 from FIG. 3 thereof;

FIG. 8 is a top side perspective view thereof; and,

FIG. 9 is a top side perspective view thereof shown in an environment of use.

The broken lines in FIGS. 1-9 depict environmental subject matter only and form no part of the claimed design.

1 Claim, 5 Drawing Sheets
